United States Patent Office

Des. 182,402
Patented Apr. 1, 1958

182,402

GLASS WASHER

Thomas H. Corbett, Chicago, Ill.

Application August 13, 1957, Serial No. 47,357

Term of patent 14 years

(Cl. D49—1)

Fig. 1.

Fig. 2.

Fig. 1 is a perspective view of a glass washer, showing my new design; and

Fig. 2 is a perspective view of the opposite side and end thereof.

I claim:

The ornamental design for a glass washer, substantially as shown.
